DUMP-CAR DEVICE.

1,057,413.

Specification of Letters Patent. Patented Apr. 1, 1913.

Application filed April 14, 1910. Serial No. 555,541.

To all whom it may concern:

Be it known that we, CHARLES H. Doty and WILLIAM L. BURNER, citizens of the United States, residing at Columbus, in the county of Franklin and State of Ohio, and JOHN M. WILCOX, a citizen of the United States, residing at Cleveland, in the county of Cuyahoga and State of Ohio, have invented certain new and useful Improvements in Dump-Car Devices, of which the following is a specification.

This invention relates to improvements in dump car devices, and especially contemplates the provision of an automatic valve trip operated by the piston in the air cylinder. Essentially a rod associated with the valve adapted to control the supply of air to the cylinder is disposed in the cylinder to be engaged by the piston when the necessary travel of the piston to dump the car is almost completed. This engagement causes the valve to be rotated and the supply of air to the cylinder is cut off.

The purpose of the device is to economize air by cutting off the flow when the need for it is past. In practice it often happens that one car in a train requires less air than another to dump, and the supply to each car should therefore be automatically controlled to lessen the expense of operation.

In the drawings is shown a construction in which a cylinder is positioned about the longitudinal middle of each side of the car, and the dumping impetus is imparted midway of the ends; in the piping system a valve is provided associated with a rod or member penetrating the cylinder to receive the impact of the moving piston when the latter is approaching the limit of its outward or dumping movement, whereby the valve is turned to its cut off position. Other constructions to accomplish this result may be made, and the construction illustrated is intended to show merely a preferred embodiment of the idea.

Referring to the drawings which accompany this description and are hereby made a part of this specification, Figure 1 is a side view of a car having the improved devices thereon; Fig. 2 is a view partly in section of the valve and tripping devices therefor associated with an air cylinder.

In the drawings 1 is the underframe of a car having the box or bed 2 thereon ar-

ranged to dump laterally to discharge the 55 contents; the cylinder 3 is appropriately placed on the frame 1, and contains the piston 4, having the stem 5 adapted to be reciprocated to dump the car. Air is admitted to the under side of the piston through the 60 pipe 6 from the pipe 7 through the passage-way 8, which is controlled by the valve 9 placed therein, and adapted for rotation to admit the air into pipe 6 or to exclude it therefrom. The valve stem 10 carries the 65 rocker arm 11, with which is pivotally associated the link 12; at 13 the link 12 is pivoted to the stop 14 carried on the rod 15. The stop 14 rests on the bracket 16 when the parts are normally positioned. 70 The rod 15 is encircled by the spring 17, and passes through the guide 18 near its upper end and through the bracket 16 near its lower end; the spring is compressed between the stop 14 and the guide 18 when the 75 rod is lifted, and by expansion tends to return the rod to normal position when the stress thereon is intermittent. At its upper end the rod 15 is hooked and inserted through the cylinder top at 19, to project 80 downwardly in the cylinder as appears at 20.

For the details of a construction for dumping the car reference is hereby made to the pending application of Messrs. Stansill, Doty, and Hubbard, Serial Number 511,662, 85 filed in the United States Patent Office on August 6th, 1909; it is in connection with dumping devices of the general kind therein illustrated that we contemplate the use of the improvements herein set forth, al- 90 though it is apparent that they may be used in connection with any dumping construction employing compressed air or other kind of motive pressure.

The operation is as follows:—Air admitted into the cylinder through pipe 6 lifts the piston 4 and the stem 5 is operated to dump the car. When the upper face of the piston 4 contacts with the end 20 of the rod 15 the latter is lifted and the rocker arm 11 is 95 rotated, thereby closing the valve 9, and the unnecessary further inflow of air is prevented. The air in the cylinder at the moment of contact between the piston and rod is sufficient to complete the dumping of the 100 car, and the parts are so regulated that merely enough air is admitted to cause the car to dump. All the cars may have equip-

ment similarly regulated, and as a result no air is lost in the dumping operation throughout the train. Changes in the positions of parts, not necessary to describe here, are 5 now effected in the valve construction shown generally at 21, to cut off the communication between pipes 6 and 7, and to permit the exhaust of air from the cylinder 3; thereupon the piston recedes and the rod 15 re- 10 turns to its normal lower position; this movement is accelerated and assured by the spring. The valve 9 is again turned to its open position by the return movement of the rod 15, and the foregoing operations are 15 repeated.

The device herein described may be applied to each side of the car, and in use that arrangement would usually be carried out; it is seen that the righting of the car bed 20 would be accomplished in the same manner as the dumping, except, of course, in a particular dumping and righting of the car bed these operations are accomplished through cylinders arranged on opposite 25 sides of the car. Consequently, economy of air is effected in the righting operation, and in all essential respects the two operations are performed in the same manner and by identical means. Cars are accordingly built 30 with both sides equipped with the device herein shown and described.

The advantage of the improvements herein described lies in their being automatically operable, thereby dispensing with the attention of an operator at each car, and economizing in the supply of air needed to effect 35 the dumping of the train.

We do not limit ourselves except in ac-

cordance with the scope of the appended claims.

What we claim is:—

1. In a dump car having an air cylinder and a reciprocating piston therein for dumping said car, a valve to control the admission of air to said cylinder, an automatic cut-off for said valve comprising a rock arm thereon, a link, guides on the exterior of said cylinder, a rod mounted in said guides associated with said link, a spring encircling said rod to return said rod to its lowered position, said rod being adapted to enter an opening in said cylinder to be engaged by said piston on its lifting stroke, whereby said valve is rocked to its closed position.

2. In a dump car having an air cylinder and a reciprocating piston thereon for dumping said car, and on the opposite side of said car an air cylinder and reciprocating piston therein for righting said car, a valve for controlling the air supplied to each of said cylinders, automatic means associated with each of said valves adapted to be so operated by said piston on its lifting stroke as to cut off the supply of air to each of said cylinders, when the dumping or righting operation has proceeded to a predetermined degree.

In testimony whereof we affix our signatures in the presence of two witnesses.

CHARLES H. DOTY.
WILLIAM L. BURNER.
JOHN M. WILCOX.
